ROOF SUPPORTS FOR MINES

Archelaius D. Allen, Shevington, near Wigan, England, assignor to Gullick Limited, Wigan, England, a British company

Filed July 31, 1961, Ser. No. 127,979

Claims priority, application Great Britain, Sept. 9, 1960, 31,114/60

7 Claims. (Cl. 61—45)

This invention is for improvements in or relating to roof supports for mines and the like.

One object of the present invention is to provide a self-advancing or "walking" roof support which is of such a construction that a relatively simple and inexpensive form of ram-means effects advancement or "walking" of the support and also pushing over of the conveyor or manoeuvring of other machinery.

According to the present invention there is provided a mine roof support comprising two roof supporting members movable with respect to one another in side-by-side relationship and operatively connected together by pressure fluid ram means adapted, when one support member is released and the other is held fixed between floor and roof, to effect such side-by-side movement in turn of the supporting members with respect to one another, said pressure fluid ram means including a cylinder attached to one of said members and opposed pistons coupled to, or engaging respectively, opposite ends of the other of said members.

In one embodiment of the invention the roof supporting member to which the opposed pistons are connected is relatively long as compared with the other roof supporting member to which the ram cylinder is connected. Both these members or parts may comprise a base on which is mounted one or more hydraulically extensible props, the upper ends of which are adapted to bear against the roof either directly or through roofing bars or a canopy or the like which is preferably attached to the upper ends of the props.

One particular embodiment of the invention will now be described, by way of example, with reference to the accompanying drawings wherein:

FIGURE 1 is a plan view of the roof support or chock, the actual ram-means being shown in section,

FIGURES 2, 3, 4 and 5 show the sequence in which the prop or chock shown in FIGURE 1 is operated to advance it and also push over the coal conveyor;

FIGURE 6 is a plan view of a modification of the chock shown in FIGURE 1, and

FIGURE 7 is an elevation partly in section of the support shown in FIGURE 1.

Referring first to FIGS. 1 and 7, the chock comprises two roof supporting members 10 and 11 respectively in side-by-side relationship. Each of said members has a base 12 or 12a on which are mounted vertical, extensible hydraulic props or legs 13 which may be of known construction and are adapted when extended to secure the support between floor and roof. Roofing bars 30 and 30a, or the like, may be positioned on the upper ends of the props 13 in the usual way. It will be noted that the base of the support 10 is about twice the length of the base of the support 11.

The ram-means for "walking" or advancing the chock towards the coal face and also for pushing over the conveyor C comprises a cylinder 14 and opposed pistons or rams proper 15 and 16. The cylinder 14 is flexibly connected to the support 11 by studs 17 and 18 on the base 12 of said support, said studs projecting into vertically elongated slots in lugs 14a on the cylinder end covers 14b, so as to enable a degree of vertical float or relative adjust-

2

ment to take place between the support 11 and the ram cylinder.

The piston rod 19 of the piston 15 is coupled, as indicated at 20, to a bracket 21 attached to the rear end of the base 12 of the support 10. The coupling 20 is also of a flexible nature and is designed to provide for vertical float or movement between the piston rod 19 and the bracket 21.

The outer end of the piston rod 22 of the piston 16 passes through a vertical slot 23 in a bracket or lug 24 attached to the forward end of the base 12 of the support 10, the piston rod beyond said bracket being formed with an enlarged head 25. Here again the arrangement provides for a degree of vertical "float" to take place between the piston rod 22 and the bracket 24.

Ports 26 and 27 are provided in the cylinder 14 for the supply and discharge of pressure fluid for the operation of the ram-means and for a similar purpose a port 28 is provided in the piston rod 19 which is of tubular form to provide a passageway between the port 28 and the space 29 between the two pistons.

FIGURE 2 shows the normal operating setting of the chock in which both the supporting members 10 and 11 are secured between floor and roof and the forward end 25 of the piston rod or ram 22 is against the conveyor C.

Presuming it is required to advance the chock and push over the conveyor the following procedure is adopted:

Firstly the props 13 of the support member 11 are lowered so as to release said support member from between the floor and roof. Pressure fluid is then supplied to the port 27 of the ram-means and as a result the support member 11 is advanced up to the conveyor as shown in FIGURE 3. The hydraulic props 13 of the support member 11 are then extended again so as to secure said support member between floor and roof.

Pressure fluid is then supplied through the port 28 so that the piston 16 is thrust forward and thereby moves over the conveyor to the position shown in FIGURE 4.

Finally, the hydraulic props 13 of the support member 10 are lowered and then pressure fluid is supplied to the port 26. This causes the ram 15 to draw the prop member 10 forwardly into the position shown in FIGURE 5. The props 13 of the support member 12 are then extended again so as to secure this member firmly between floor and roof. Thus, the chock is in the same condition as shown in FIGURE 2 except, of course, that it and the conveyor have been advanced an appropriate distance towards the coal face.

FIGURE 6 shows how two supports, similar to that just described, can be arranged to work together in parallel relationship, two separate support members 11 being associated with and located on either side of a single support member 10'. In general the construction of the chock or support shown in FIGURE 6 is similar to that already described and like reference numerals have been used to designate like parts.

The arrangement shown in FIGURE 6 can be modified by mounting the cylinders 14 on the support member 10' and the opposed rams on the support members 11, the lengths of said support members being adjusted accordingly. In other words, there may be a central support 11 with two supports 10' one on either side of it.

Typical advantages of the roof support above described are that it gives a true "walking" characteristic in that it can move forward without necessarily having to be attached to the conveyor or associated with an abutment member independent of itself. Furthermore, it provides for independent advance of the conveyor without requiring additional ram-means or attachments other than that embodied in it for providing its own "walking" characteristic or advancement.

A support as above described is particularly applicable

on inclined seams in that the ram-means act as a guide in the vertical slots and therefore units are drawn forward perfectly parallel to one another.

Other advantages are reduction in face cost in that only one ram per two support members or units is required, all the legs are floor mounted, thus giving advantage in low seams and the conveyor movement does not affect ram anchorage.

I claim:

1. A self-advancing mine roof prop comprising a pair of horizontally elongated, longitudinally extending roof support members, a single hydraulic forwardly advancing means connecting said members in side-by-side relation for location adjacent a forwardly positioned conveyor, said advancing means including a longitudinally extending cylinder, a pair of opposed pistons in said cylinder having forwardly and rearwardly extending rods of substantially equal length which protrude from opposite longitudinal ends of the cylinder, said cylinder being operatively connected with one of said roof support members for forward longitudinal movement of said one member relative to the other member and the rearwardly extending rod being operatively connected with the other of said roof support members for independently moving said other member longitudinally forward relative to said one member, the forwardly extending rod being guidedly supported by said other roof support member and having its forward end movable forwardly beyond said other member a selected distance corresponding to the desired forward advance of a conveyor when engaged by said end, and said pistons each being slidable in said cylinder with a stroke at least equal to said selected distance.

2. A self-advancing mine roof prop according to claim 1 wherein said pair of pistons are spaced apart slightly in the cylinder when both support members are secured in roof supporting condition prior to advance of one of said members, and ports are provided in said cylinder including communicating duct means for entry of pressure fluid in front of, behind and between said slightly spaced pistons.

3. A self-advancing mine roof prop according to claim 2 wherein said communicating duct means includes a passageway through one of the rods for introducing pressure fluid between said pistons.

4. A self-advancing mine roof prop according to claim 1 wherein said other roof support member is provided with roof support legs spaced longitudinally further apart than roof support legs provided on said one roof support member so that at least one leg of said one member will be always positioned between sidewise projections of the legs of said other member.

5. A self-advancing mine roof prop according to claim 1 wherein said forwardly and rearwardly extending rods are connected to said other roof support member by means comprising vertically elongated slots and pin constructions to permit relative vertical movements of the cylinder and rods with respect to said other support member.

6. A self-advancing mine roof support according to claim 1 wherein said other roof support member has a long rigid base and said one roof support member has a substantially shorter rigid base.

7. A self-advancing mine roof support comprising two longitudinal outer support members and a longitudinal intermediate support member between said outer support members, each of said support members having hydraulic leg means for securing it between floor and roof, and double acting ram means connecting said members together in side-by-side relationship and for guiding and effecting alternate relative advancement of the outer support members and the intermediate support member when said outer support members and said intermediate support member are alternately released from between floor and roof, and for pushing over a conveyor towards the coal face, the intermediate support member having leg means spaced longitudinally further apart than the leg means of the outer support members so that at least one leg means of each outer support member will be always positioned between sidewise projections of the legs of the intermediate support member, said hydraulic ram means comprising two cylinders, means securing said cylinders respectively one to each outer support member, a pair of opposed pistons in each cylinder, said opposed pistons having rods which protrude forwardly and rearwardly respectively from opposite ends of their cylinder, one piston rod of each cylinder extending forwardly and vertically movably through an apertured member on the front end of said intermediate support member and having its forward end movable forwardly beyond said intermediate support member a selected distance for pushing a conveyor, the other piston rod of each cylinder extending rearwardly of its associated outer support member and having means vertically movably connecting the outer end thereof to the rear end of the intermediate support member, the lengths of the piston rods of each pair being such that when the three support members are secured in roof supporting position, the two pistons of each pair are at a position of close approach in their cylinder with a small space between them, means for introducing pressure fluid into space between the pistons of each pair and means at both ends of each cylinder for introducing pressure fluid thereto in front of and behind the respective pistons of each pair.
